[57] CLAIM

The ornamental design for a combined beverage maker and dispenser machine, substantially as shown and described.

DESCRIPTION

FIG. 1 is a front perspective view from the right and above of a first embodiment of a combined beverage maker and dispenser machine, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a front perspective view from the right and above of a second embodiment of a combined beverage maker and dispenser machine, showing my new design;

FIG. 8 is a front elevational view thereof;

FIG. 9 is a rear elevational view thereof;

FIG. 10 is a top plan view thereof;

FIG. 11 is a bottom plan view thereof; and

FIG. 12 is a left side elevational view thereof.
